UNITED STATES PATENT OFFICE

MARK H. MARTIN, OF READING, PENNSYLVANIA, ASSIGNOR TO BIRDSBORO STEEL FOUNDRY & MACHINE COMPANY, OF BIRDSBORO, PENNSYLVANIA, A CORPORATION OF PENNSYLVANIA

SIDE FRAME FOR CAR TRUCKS

Application filed December 11, 1928. Serial No. 325,269.

My invention relates to side frames for railway car trucks.

The general object of my invention is to provide a side frame for car trucks of novel construction wherein the compression, tension and other members or parts thereof are so constructed and reinforced as to greatly increase the strength of the said frame in the regions thereof which are subjected to maximum stresses.

It also is an object of my invention to provide a novel side frame for railway car trucks comprising journal boxes cast integrally with the said side frame and compression and tension members, which members are of general U-shape in cross section, the transverse strength of the said members being increased in proportion to the weight thereof by distributing the metal of the webs of the said members outwardly from the neutral axes of the said members.

A further object of my invention is to provide a novel cast side frame for railway cars of the type in which spaced bolster columns 25 extend between the compression and tension members of the said frame, the said compression and tension members being of general U-shape in cross section, the portion of the web included between the base portions of 30 the bolster columns being curved so that a greater percentage of the forces imposed upon the frame by the load carried thereby will be exerted in the direction of the length of said web and being provided with a novel 35 and improved spring plank seat having greater strength and offering greater resistance to stresses than has been the case in similar constructions which have been devised heretofore.

Another object of my invention is to provide a novel construction of side frame for railway cars wherein journal boxes are cast integrally with the said frame, the journal boxes being so constructed and reinforced as 45 to resist the tendency of the said boxes to bulge upon application of pressure to the bottom sides thereof by the engagement of a jack or the like therewith for raising the car truck and car underframe and car body supported upon said frame to effect repairs.

It also is an object of my invention to provide a novel construction of side frame which is characterized by the provision of tension and compression members of general U-shape in cross section, the webs of which members are thinner at and near the neutral axes thereof than the adjoining marginal portions of the said webs in order to secure increased transverse strength in proportion to the weight of the said members, 60 the flanges of the said members having beading formed thereon at their outer edges.

Another object of my invention is to provide an integral cast side frame of novel character which includes brake hanger brackets, 65 which are characterized by the provision of removable or replaceable bearings therefor.

Other objects and advantages of the invention from a practical standpoint will be pointed out in the detailed description there- 70 of which follows or will become apparent from such description.

In order that the invention readily may be understood and its manifold practical advantages appreciated, reference may be had to the accompanying drawings, in which I have illustrated a structure embodying the said invention in the form which is at present preferred by me. But it is to be understood that the invention is susceptible of embodiment in other forms of construction than that shown in the drawings and that changes in the details of construction may be made without departing from the spirit of the said invention.

In the said drawings:—
Fig. 1 is a view partly in side elevation and partly in longitudinal vertical section of a cast side frame embodying my invention;

Fig. 2 is a view in top plan of a portion of the side frame shown in Fig. 1;

Fig. 3 is a view in vertical transverse section through one of the journal boxes connected to the side frame, the said view being taken on the line 3—3 of Fig. 2;

Fig. 4 is a view in vertical transverse section of the upper part of the inside portion of a journal box taken on the line 4—4 of Fig. 2;

Fig. 5 is a view in bottom plan of a portion of the side frame shown in Fig. 1;

Fig. 6 is a horizontal sectional view taken on the line 6—6 of Fig. 1;

Fig. 7 is a view in transverse section taken on the line 7—7 of Fig. 1;

Figs. 8, 9 and 10 are transverse sectional views taken respectively on lines 8—8, 9—9 and 10—10 of Fig. 1; and

10 Figs. 11 and 12 are transverse sectional views similar to those shown in Figs. 8, 9 and 10 but taken through a side frame construction embodying modified bolster columns, and tension and compression members.

15 Referring to the drawings, 1 designates the compression member and 2 the tension member of my novel side frame construction. Spaced bolster columns 3 extend between and are cast integrally with the said 20 compression and tension members. The presence of the said bolster columns 3 provides the usual bolster window. The central portion of the compression member 1 is curved or cambered as shown at 4, the side 25 portions of the said member between the ends of the curved portion 4 and the outer ends of the compression member being substantially straight, as shown. Such construction of the compression member provides 30 maximum resistance against bending or compression stresses.

The columns 3, the compression member 1 and the tension member 2 are of general U-shape or channel shape in cross section, as 35 is clearly shown respectively in Figs. 8, 9 and 10. Referring to the said figures, it will be observed that the webs 8, 9 and 10 of the bolster columns and the compression and tension members, respectively, increase in 40 thickness from their neutral axes to the marginal edge portions thereof. By distributing the metal of the webs of these parts so that there is a thickening thereof from the neutral or central axes thereof to their outer 45 edges it has been found that the resistance thereof to lateral bending and twisting stresses is greatly increased. Such distribution of the metal preferably is effected by curving the inner side of the web on an arc 50 having a radius R substantially greater than the depth or depths of the various channel sections.

In Fig. 11 I have shown a modified cross section of a channel member which may be 55 employed in lieu of either of those shown in Figs. 8, 9 and 10. In the said figure the desired distribution of the metal away from the neutral axis of the channel member may be described as being effected by providing 60 straight converging inner surfaces 12 which merge into a curved surface 13 the radius R' of which is approximately equal to the maximum depth of the channel member.

In Fig. 12 is shown another modified channel member in cross section in which the

inner inclined sides 14 meet at an angle at the neutral axis of the web of the said member.

The edges of the members 1 and 2 and the columns 3 are provided with inwardly extending flanges 15, 16 and 17, respectively. The ends of the said flanges merge and form or provide openings 18 of general triangular shape. In order to reinforce the edges of the said flanges beading 19 is provided which 70 beading surrounds the openings 18. The beading which extends along the edges of the flanges 17 is of less width than the beading which extends along the edges of the flanges 15 and 16. The width of the latter 75 increases outwardly to the points at which the said flanges 15 and 16 merge, at which points the beading 19 is of maximum width, as shown at 20. The beading 19 is of varying width in order that the resistance to 80 cracking or breaking of the various flanges on which it is provided shall be in proportion to forces liable to be imposed thereon in 85 different localities.

The central portion of the flange 15 bordering the bolster window also is provided with beading, as shown at 21. This beading diminishes in width from the middle of the length thereof outwardly, and the said beading is connected with and merges into the 90 beading 19, as shown at 22. Such arrangement of the beading 21 has been found to materially strengthen and reinforce the side 95 frame.

The central portion of the web 10 of the tension member 2 which forms the bottom of the bolster window is curved to points A and B located slightly beyond or outside of the bases of the bolster columns 3. The said portion is so curved as to occupy the position 100 which it would occupy if the tension member were flexible and were suspended at its opposite ends, the side portions of the said tension member extending outwardly along substantially straight lines, as shown. The top 105 side of the curved portion of the web 10 is provided with upwardly, transversely and longitudinally extending ribs 23 the top edges of which terminate in a common plane. Drain holes 23a are formed in the said web 110, as shown, to permit water to drain from the spaces formed between the ribs and the said web. Connected preferably integrally 115 with the said ribs and with the member 6 are outwardly projecting shelves 24 the top sides of which are located in the same plane as the top edges of the said ribs. Bosses 25 are or may be formed on the top sides of the shelves 120 24 for engaging and holding in position a suitable spring plank (not shown). The ribs 23 and the shelves 24 constitute a seat for the said spring plank, the said seat being located in a plane below which a portion of the web 125 10 extends, and the ends of the said seat merging with the said web. It also will be

seen that the said ribs and shelves reinforce and strengthen the lower central portion of the tension member and that the bases of the columns 3 are connected to the top side of the web 10 by curved portions 24a which merge with the latter adjacent the ends of the spring plank seat. The ends of the side edges of the shelves 24 taper inwardly with respect to the side frame and are bent upwardly to meet the sides of the said member 2 thereby providing strengthening portions 26. Triangular gusset portions 27 extend upwardly from the said shelves and are joined with the corners of the bolster columns 3, as is clearly shown in Fig. 7, and operate to strengthen the structure greatly at those points.

Directly underneath the bolster window the tension member 2 is of general rectangular shape in cross section, as will be seen by referring to the said Fig. 7. As shown in the said figure the under side 28 of the central portion of the web 10 preferably is curved transversely in order to reduce the thickness of the said web along its neutral axis and to increase the thickness of the marginal edge portions thereof. The flanges 29 which extend downwardly from the opposite edges of the central portion of the web 10 connect with the bottom web 32 the inner side of which also is curved in the same manner as the web 10, as shown at 33. The outer ends of the web 32 and of the flanges 29 are curved upwardly and connect with the under side of the web 10 of the tension member, as is indicated at 34 in Figs. 1 and 5. As a result of this construction the resistance of the tension member to forces applied in the direction indicated by line $x-x$ as well as other directions, is greatly increased. Preferably gussets 35 are provided between the bottom sides of the shelves 24 and the outer sides of the flanges 29. The web 32 is provided with drain holes, as shown at 36 in Figs. 1 and 5. The portion of the structure comprising the parts 29, 32 and the adjoining part of the web 10 may be referred to as a closed box section.

The straight side portions of the tension member extend in converging relation to the straight side portions of the compression member toward the curved or cambered portions 38 of the said compression member near the outer ends of the frame at which points the journal boxes 39 are connected integrally to the said frame. The outer ends of the web 10 of the tension member meet and are connected integrally at 40 with the central portions of the edges of the roofs 41 of the said journal boxes, as shown, while the flanges 15 and 16 merge with each other adjacent the said boxes. The web 9 of the compression member does not connect directly with the roofs of the journal boxes, being cut away, as indicated at 42. The

flanges 15 of the compression member extend over and are connected to the said roofs, the outer edges thereof being curved inwardly and terminating in the planes of the outer side walls of said boxes, as shown at 43. The union between the journal boxes and the webs 10 is strengthened by gussets 44 which extend from the inner side walls 45 of the said boxes to the edges of the said webs.

In order to prevent collapsing of the journal boxes upon the application of lifting forces to the under sides thereof by means of a lifting jack I have provided ribs or corrugations 46 in the bottoms 47 of the said boxes. These ribs or corrugations preferably extend inwardly and longitudinally of the said boxes to points slightly beyond the middles thereof, as shown in Fig. 3. To further obviate the tendency of the bottoms of said journal boxes to bulge inwardly the lower portions 48 of the sides of the said boxes which are located in front of the circular portions 48a of the wider rear parts of the said boxes, are so constructed as to present maximum resistance to forces which tend to cause deformation of the said boxes. I have found that by making the portions 48 of the said boxes substantially plane and extending them upwardly in diverging relation to each other, as shown, the desired results are obtained. By means of this construction, when pressure is applied to the bottoms of the journal boxes the pressure is resisted by the corrugations 46 and also is transmitted outwardly, as it were, from the centers of the journal boxes to and through the inclined plane side portions 48 thereof.

Adjacent the top ends of the bolster columns 3 but located laterally thereof and connected to the rear or inner side of the compression member 1 are brake hanger brackets. These brackets preferably are cast integrally with the compression member of the side frame and each of them comprises a horizontal portion 49 to which is connected a substantially vertical portion 50 the lower end portion of which is of general hook-shape, the curved portion 51 thereof having a laterally projecting lip portion 52 connected thereto. The lip portion 52 has a recess formed therein, as shown at 53 in Fig. 2. This recess is adapted to receive a lug 54 formed on a bearing 55 while the curved portion 51 of the bracket is adapted to receive the said bearing. The upper end portions of brake hangers, a portion of one of which is shown at 57 in Fig. 1, are journaled in the bushings 55. The said bearings are secured to the brackets by means of bolts and nuts, indicated at 58.

It now will be seen that I have provided a side frame construction for railway car trucks of novel character. By providing a side frame having reinforcing means of the character described herein, and by constructing the various elements or sections of the said side frame in accordance with my inven-

tion, I am able to produce side frames of greater strength in proportion to their weight than those which have been devised heretofore.

5 Having thus described my invention, what I claim and desire to secure by Letters Patent is:

10 1. A side frame comprising a compression member, a tension member, spaced bolster columns interposed between the said mem-

15 bers the central portion of the said compression member being curved, the said members and the said bolster columns being of channel shape in cross section, and the webs of the said columns and members being thinner in the regions of their neutral axes than the marginal edge portions thereof.

20 2. A side frame comprising a compression member, a tension member, spaced bolster columns interposed between the said mem-

25 bers, the central portion of the said compression member being curved longitudinally, upwardly extending ribs formed integrally with the top side of the central portion of the tension member, which ribs extend transversely and longitudinally of the said tension member, the upper edges of the said ribs terminating in a common plane, and shelves formed integrally with the said tension mem- 30 ber and the said ribs, the top sides of the said shelves being located in the same plane as the top edges of the said ribs, the said shelves and the said ribs constituting a spring plank seat.

35 3. A cast side frame comprising compression and tension members, and journal boxes connected integrally to the outer ends of the said side frame, the bottoms of the said boxes having corrugations formed therein which corrugations extend longitudinally of the 40 said boxes.

4. A cast side frame comprising compression and tension members, and journal boxes connected to the outer ends of the said side frame, the bottoms of each of the said jour-

45 nal boxes having corrugations formed therein extending longitudinally of the said boxes, and the lower front side portions of the sides of the said boxes being substantially plane and extending upwardly in diverging relation to each other.

50 5. An integral side frame comprising brake hanger brackets, each of the said brackets comprising hook portions, and bearings seated in the said hook portions, and means for securing the said bearings to the said brackets.

55 6. An integral side frame comprising brake hanger brackets, each of said brackets comprising a hook bearing having a laterally ex- 60 tending lip portion connected thereto, which lip portion has a recess formed therein, and a bearing adapted to fit in the said hook portion, the said bearing having a lug thereon adapted to fit in the said recess.

65 7. A side frame for car trucks comprising

compression and tension members, spaced bolster columns interposed between the said members, the said members and the said columns being of channel shape in cross section, and the flanges of the said members and columns merging to form openings of general triangular shape, beading formed on the edges of the said flanges surrounding the said openings, the beading increasing in width from the inner ends of the portions thereof formed on the flanges of the compression and tension members to the outer end portions thereof, and the central portions of the flanges of the compression member adjacent the bolster columns also having beading formed thereon, which beading diminishes in width from the central to the outer end portions thereof, the outer ends of the said last named beading being connected to the said first named beading.

8. A side frame for car trucks comprising compression and tension members, spaced bolster columns interposed between the said members, the said members and the said columns comprising webs having flanges formed on the edges thereof, the said webs being reduced in thickness in the region of the neutral axes thereof, the flanges of the said members and columns merging to form openings of general triangular shape, beading formed on the edges of the said flanges surrounding the said openings, which beading increases in width from the inner ends of the portions thereof which are formed on the flanges of the compression and tension members to the outer ends of the said portions, and the central portions of the flanges of the compression member adjacent the bolster columns also having beading extending along the edges thereof, which beading diminishes in width from the middle to the outer end portions thereof, the outer end portions of the last named beading being connected to the said first named beading.

9. A side frame for car trucks comprising compression and tension members, spaced bolster columns interposed between the said members the presence of which causes a bolster window to be formed, the said members and the said columns comprising webs having flanges connected to the edges thereof, the central portions of the said webs being reduced in thickness, the upper central portion of the said tension member being curved and having upwardly extending ribs formed integrally with the top side thereof, the said ribs extending transversely and longitudinally of the said tension member and the upper edges thereof terminating in a common plane, and shelves formed integrally with the said tension member and the said ribs, the top sides of which shelves are located in the same plane as the top edges of the said ribs, the said shelves and the said ribs constituting a spring plank seat in a

plane above the said curved central portion of the said tension member.

10. A side frame for car trucks comprising compression and tension members, which members have central curved portions, spaced bolster columns interposed between the said members the presence of which causes a bolster window to be formed, the said members and the said columns comprising webs having flanges connected to the edges thereof, the central portions of which webs are reduced in thickness with respect to the marginal portions thereof, the flanges of the said members and columns merging to form openings of general triangular shape, beading formed on the edges of the said flanges surrounding the said openings, which beading increases in width from the inner ends of the portions thereof which extend along the flanges of the compression and tension members to the outer ends of the said portions, the central portions of the flanges of the compression member adjoining the said bolster window also having beading formed thereon which diminishes in width from the middle to the outer end portions thereof, the outer end portions of the last named beading being connected to the first named beading, upwardly extending ribs formed integrally with the top side of the curved portion of the said tension member, which ribs extend transversely and longitudinally of the said tension member, the top edges of the said ribs terminating in a common plane, and shelves formed integrally with the said compression member and the said ribs, the top sides of which shelves are located in the same plane as the top edges of the said ribs, the said shelves and the said ribs constituting a spring plank seat.

11. A side frame for car trucks comprising compression and tension members, spaced bolster columns interposed between the said members the presence of which causes a bolster window to be formed, the said members and the said columns comprising webs having flanges connected to the edges thereof, the central portions of which webs are reduced in thickness with respect to the marginal portions thereof, the flanges of the said members and columns merging to form openings of general triangular shape, beading formed on the edges of the said flanges surrounding the said openings, which beading increases in width from the inner ends of those portions of the beading which extend along the flanges of the compression and tension members to the outer ends of the said portions, the central portions of the flanges of the said compression member adjacent the said bolster window also having beading formed on the edges thereof, which beading diminishes in width from the middle to the outer end portions thereof, the outer end portions of the last named beading being

connected to the first named beading, and journal boxes connected integrally with the outer ends of the said side frame, the lower front side portions of which boxes are plain and are inclined upwardly in diverging relation to each other.

12. A side frame for car trucks comprising compression and tension members, spaced bolster columns interposed between the said members, the said compression and tension members having central curved portions, the said members and columns comprising webs having flanges connected to the edges thereof, the central portions of which webs are reduced in thickness with respect to the marginal portions thereof, and journal boxes connected integrally to the outer ends of the said side frame the bottoms of which boxes have corrugations formed therein extending longitudinally with respect thereto, the lower front side portions of the said boxes being plane and extended upwardly in diverging relation to each other.

13. A side frame for car trucks comprising compression and tension members, spaced bolster columns interposed between the said members, the central portions of the said members being curved, the said columns and members comprising webs having flanges connected to the edges thereof, the central portions of which webs are reduced in thickness with respect to the marginal portions thereof, upwardly extending ribs formed integrally with the top side of the said central portion of the tension member, the top edges of which ribs are located in a common plane, shelves formed integrally with the said central portion of the said tension member and extending laterally with respect thereto, the top sides of which shelves are located in the same plane as the top edges of the said ribs, and journal boxes connected integrally to the outer ends of the said side frame, the bottoms of which journal boxes are provided with corrugations, the lower front sides of the said journal boxes being substantially plane and extending upwardly in diverging relation to each other.

14. A side frame for car trucks comprising compression and tension members, bolster columns interposed between said members, the said members and columns comprising webs having flanges connected to the edges thereof, the central portions of the said webs being reduced in thickness with respect to the marginal portions of the said webs, upwardly extending ribs formed on the top side of the central portion of the said tension member, shelves formed integrally with and extending laterally with respect to the said central portion of the said tension member, the top edges of the said ribs and the top sides of the said shelves being located in a common plane, journal boxes connected integrally to the outer ends of the said side frame, the

lower front side portions of which journal boxes are substantially plane and are inclined upwardly in diverging relation to each other, and brake hanger brackets formed integrally with the said frame, each of which brackets comprises a hook portion having a laterally extending lip, a recess formed in the said lip and a removable bearing adapted to fit the hook, said bearing having a lug formed thereon adapted to fit in the said recess.

10 15. A cast side frame comprising compression and tension members, and journal boxes connected to the outer ends of the said side frame, the bottoms of each of the said journal boxes having corrugations formed therein extending longitudinally of the said boxes, and the lower side portions of said boxes, which are located in front of the circular portions of the wider rear parts of the said boxes, 20 being substantially plane and extending upwardly in diverging relation to each other.

16. A cast side frame comprising a compression member, a tension member, spaced bolster columns interposed between said members, the central portion of the said tension member between the said columns being curved longitudinally, a spring plank seat formed on said tension member and located in a plane below which a portion of the 30 said member extends, the said columns being connected to the top side of the said tension member by curved portions which merge into the latter near the adjoining ends of the said spring plank seat, the outer portions of the 35 said tension member being channel shaped in cross section, and journal boxes connected to the outer ends of the said frame, the ends of the webs of the outer portions of said tension member being connected to the central portions 40 of the roofs of said journal boxes.

17. A side frame comprising a compression member, a tension member, spaced bolster columns interposed between said members and forming a window opening in the 45 said frame, the central portion of the said tension member between said columns being curved longitudinally to points located outside of the corners of the said window, between which points the said tension member 50 is of general rectangular shape in cross section, and a spring plank seat formed on said tension member and located in a plane below which a part of the said central curved portion of the said member extends.

55 18. A side frame comprising a compression member, a tension member, spaced bolster columns interposed between said members, a portion of said tension member which extends to points beyond said bolster columns 60 consisting of a closed box section and being of general rectangular shape in cross section, the outer portions of the said tension member being of channel shape in cross section.

65 19. A side frame for railway cars having

thereon brake hanger brackets each of said brackets comprising a laterally extending portion having a recess extending across its inner end portion, a bearing for a brake hanger mounted in the said recess the said bearing having an outwardly projecting portion, and means for securing the said outwardly projecting portion to the outer end part of the laterally extending portion of the said bracket.

70 20. A side frame for railway cars comprising brake hanger brackets each of the said brackets having vertically and laterally extending portions, the said laterally extending portion being provided at its inner end 80 with a transversely extending recess, a bearing for a brake hanger mounted in the said recess, and means for detachably securing the said bearing to the said hanger.

75 21. A side frame comprising a compression member, a tension member, spaced bolster columns interposed between the said compression and tension members, the said tension member having a web the edges of the 90 central portion of which are provided with depending flanges, the edges of the opposite ends of the said flanges extending inwardly toward the said tension member and merging into the web thereof at points beyond the said bolster columns, and a web secured to the 95 lower edges of the said flanges and inclosing the space between the said flanges, the opposite ends of the said web extending inwardly toward the said tension member and being connected thereto at points beyond the said 100 bolster columns.

105 In testimony that I claim the foregoing as my invention, I have hereunto signed my name this 8 day of December, A. D. 1928.

MARK H. MARTIN.
